TOILET KIT FOR MEN

Michael Janchick, Hot Springs National Park, Ark.

Application September 19, 1944, Serial No. 554,740

1 Claim. (Cl. 132—79)

My invention relates to improvements in toilet kits for men, the primary object in view being to provide an inexpensive, light in weight, and compact toilet kit of the folding box type, which is simple in construction, involves a minimum number of parts, and is adaptable to accommodate, without the use of individual boxes and straps, all the essential toilet accessories of the predominating standard type, such as the safety razor, shaving brush, tooth brush, an extra supply of safety razor blades, a loose mirror, comb, and manicuring implements, including a number of containers for toilet preparations, and which, when in open position, will have every article therein readily accessible for instant use without removal of any other item in the case, and which, when closed, will retain all the articles fully secured against displacement.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a view in perspective illustrating my improvements in the toilet kit.

Figure 2 is a view in perspective illustrating the toilet kit complete with contents.

Figure 3 is a sectionalized view taken on line 3—3 of Figure 2, illustrating the positions of the toilet accessories rack and of the containers for toilet preparations in relation to the length and the combined depth of the case and cover when closed.

Figure 4 is a separately drawn view of the curved rest for the bristle portion of the shaving brush.

Figure 5 is a view of the toilet accessories rack drawn separately to illustrate the constructional features thereof.

Figure 6 is a sectionalized view taken on line 6—6 of Figure 2, illustrating the hinged toilet accessories rack in upwardly swung position, and the relative positions of the curved rest and of the shaving brush.

Referring to the drawings by numerals, my improved toilet kit consists of a tray type case 1, and a tray type cover 2 which is hinged to the said case 1, as at 3; a pivoted catch 4, attached to the front wall of cover 2, and a stud 5, attached to the front wall of the said case 1, are provided to fasten the said cover when closed.

The cover 2 has a centrally located recess 6 55

which forms a proportional extrusion 41 on the top side of the said cover, thus providing means for accommodation of mirror 7, the said mirror to be retained in the said recess by strap 8 which extends lengthwise across the said recess, with the ends of the said strap securely attached at the short edges of recess 6.

A curved rest 9, securely attached to the bottom of the said case 1, as shown in Figure 1 and Figure 6, is provided for retaining the bristles of the shaving brush in normally rounded condition.

An elongated, rectangular rack 10, occupying a part of the space within the said case 1, is provided to accommodate toilet accessories as illustrated in Figure 2. The said rack 10 is hinged to the rear wall of the said case 1, as at 11 of Figure 6, so as to permit the free end of the said rack to be swung upwardly and out of said case 1, thus facilitating a ready access to the shaving brush 33 which is normally carried on the bottom of the said case 1, directly underneath, parallel to, and within the confines of the said rack 10.

The said rack 10 is comprised of side walls 12 and 13, a rear wall 14, and a front wall 15, including an intermediate cross bar 16, and the transverse partitions 17 and 18, which, together with the slightly arched bottom wall 19, form within the said rack 10 equally partitioned pockets 20, 24, and 27. The purpose of the said pockets will presently be made clear.

The side walls 12 and 13, and the front wall 15, of the said rack 10, having arched undercuts and thus forming the rear legs 31, and the front legs 32 of the said rack 10, the said rear and front legs, when resting on the bottom of the said case 1, are adaptable to straddle the said curved rest 9 in between the said rear legs 31, and the handle of the shaving brush in between the said front legs 32, thus retaining the shaving brush 33 on the bottom of the said case 1 and within the confines of the said rack 10. A bracket type keeper 34 is attached to the side wall 12 of the said rack 10 to accommodate finger nail file 35 by inserting the blade of the said file into the said keeper, a similar type keeper 36 is provided on the side wall 13 of the said rack 10, to accommodate scissors 37 in like manner.

Pocket 20 within the said rack 10, having a top ledge 21 at one end, and a notch 22 at the other end of the said pocket, provide means for the accommodation of a tooth brush 23 with the bristle portion of the said tooth brush inserted downward into the said pocket and partly under the said top ledge 21, thus retaining the said

tooth brush in horizontal position with the handle thereof extending through the said notch 22 to overlie the nozzles of a number of containers 38 located within the said case 1.

Pocket 24, with the notch 26 in partition 18 of the said rack 10, provide means for the accommodation and easy withdrawal of the safety razor blades 25, which are carried in the said pocket 24.

Pocket 27, with the notch 29 in the cross bar 16, and a notch 30 in the front wall 15 of the said rack 10, provide means for accommodation of assembled safety razor 28 in the said pocket 27, with the razor handle extending horizontally to rest in the said notches 29 and 30.

A space 40 within the said case 1, parallel to and adjoining the said rack 10 is provided to accommodate a number of containers 38 for toilet preparations and a comb 39 located within the said case 1 along the bottom ends of the said containers 38.

The improved toilet kit as described and illustrated herein, consisting of a tray type case and a tray type cover hinged thereto, including the fixed curved rest and the hinged rack for toilet accessories within the case may be made of any material suitable for the purpose.

The contents within the case, including the mirror in the recess of the cover, when arranged in their respective positions as illustrated in Figure 2 of the drawings form a relatively level surface as shown in Figure 6, so that, with the cover closed, all the articles in the kit will be securely retained against vibration and against displacement.

The foregoing will, it is believed, suffice to impart a clear understanding of my improvements in toilet kits for men, wherein the new and useful structure illustrated in Figure 5, and in assembled positions in other drawings, constitutes the basis for the subjoined claim.

What I claim is:

In a toilet kit, comprising an elongated, rectangular case of a tray type, and a hinged cover for the said case, an elongated, rectangular rack provided with supporting legs adapted for straddling purpose and having a rear end hinged to the rear side wall of the said case for upwardly swinging movement for purpose described, said rack occupying space in one end of the said case, thus providing the adjoining lateral space within the said case for accommodation of a plurality of toilet containers and other toilet articles, the said rack being also provided with a plurality of pockets for accommodation of essential shaving accessories, including a means adapted for accommodation of a tooth brush with the handle of the said tooth brush extending horizontally to overlie the said containers, said means comprising a pocket in said rack for the bristle end of the said tooth brush, a ledge in said pocket under which the said bristle end may be inserted, and a notch in one side of the said rack adapted to accommodate the handle of the said brush, thus permitting horizontal extension of the said handle to overlie the said containers.

MICHAEL JANCHICK.
